PRESS INKING DEVICE

Charles T. Walter, Chicago, Ill., assignor to Industrial Patents Corporation, Chicago, Ill., a corporation of Delaware

Application June 5, 1936, Serial No. 83,645

11 Claims. (Cl. 101—340)

This invention relates to an inking device.

One of the objects of the invention is to provide means for uniformly introducing a supplementary fluid into the ink supply of a printing press.

Another object of the invention is to provide means for continuously introducing a volatile fluid into the ink supply of a printing press for mixture therewith during the printing operation.

10 Another object of the invention is to provide means for continuously and uniformly incorporating a highly volatile fluid in the ink supply of a printing press during the printing operation to assure maximum strength of the volatile 15 fluid in the ink at the time of printing.

Another object of the invention is to provide means for maintaining volatile ingredients of an ink mixture at full strength throughout the printing operation.

20 Another object of the invention is to provide a printing press having means for continuously maintaining a supply of ink adapted for printing upon protein surfaces such as skins, membranes and protein films.

25 Other objects of the invention will be apparent from the description and claims which follow.

It has been proposed from time to time to mark sausage products in various ways. Direct printing upon natural sausage casings prepared from 30 animal intestines, however, has been inherently fraught with difficulty due to the nature of the tissue. Also, due to the fact that these casings are wetted during stuffing and processing, it is extremely difficult to cause ink to adhere to the 35 casing surface.

In my copending application, Serial No. 23,669, filed May 27, 1935, now Patent No. 2,054,148, Sept. 15, 1936, I have described a method for direct printing on animal casings which are given no 40 treatment other than that normally accorded animal casings, printing directly upon the surface of the casing with an ink containing a protein precipitant such as formaldehyde.

Formaldehyde is highly volatile and due to the 45 large area of the inking plate of the conventional printing press, will evaporate in large measure before the ink is consumed in the normal printing operation. Without the addition of a further formaldehyde solution to the mass, it is found 50 that the inking plate must be periodically wiped clean and a fresh ink supply added to the press at short intervals to assure a satisfactory formaldehyde concentration in the ink.

In accordance with the present invention, a 55 supply of ink containing an aldehyde solution is

spread upon the inking plate of the printing press. Thereafter and during the printing operation, a fresh aldehyde solution is continuously fed drop by drop to the ink supply on the said inking plate to compensate for the aldehyde solution normally passing from the ink mass by evaporation. The added solution is thoroughly admixed with the ink mass by relative movements of the inking rollers in contact with the inking plate. It will, therefore, be seen that the present invention contemplates an ink containing volatile ingredients of full strength throughout the printing operation.

Referring now to the drawing, in which similar characters of reference are used to designate similar elements.

Figure 1 is a side elevational view illustrating the device of the present invention mounted relative to the inking plate of a printing press.

Figure 2 is a perspective view of a printing press utilizing the device of the present invention.

In the drawing, 1 designates a conventional press having a rotary inking plate 2 and inking rollers 3, 4 and 5, adapted as a group to move backwardly and forwardly alternately in contact with the inked surface 6 of plate 2 and the surface of the printing type mounted in the press. Plate 2 is rigidly secured to shaft 7 at 8, which shaft 7 passes through bearing 9 into housing 10. Rotary motion is translated to plate 2 through shaft 7 by suitable drive mechanism in housing 10, not shown. At each cycle of the press, the plate 2 is rotated substantially 90°, so that at each cycle the rollers 3, 4 and 5 pass over a different portion of the area of plate 2. This has the effect of uniformly distributing the ink mass over the entire surface of plate 2 and over the surface of the individual rollers.

Rollers 3, 4 and 5 are respectively mounted upon shafts 11, 12, and 13, journaled within bearings 15 and 16, 17 and 18, and 19 and 20. Bearings 15, 17 and 19, and 16, 18 and 20 are respectively connected to swinging arms 21 and 22, the motion of which is controlled by suitable mechanism mounted within press 1. The mechanism for operating plate 2 and arms 21 and 22 are relatively driven, such that rotary movement is imparted to plate 2 when the rollers 3, 4 and 5 are out of contact therewith.

In accordance with the present invention, formaldehyde solution is continuously fed drop by drop to the inking surface of plate 2 during the printing operation, each individual drop being thoroughly incorporated with the ink mass on

plate 2 through the relative movements of plate 2 and rollers 3, 4, and 5, hereinbefore described. This is accomplished through the medium of vessel 23 mounted above plate 2 preferably in a manner to direct the individual droplets of the aldehyde solution against printing surface 6 of plate 2 at substantially the center thereof. Vessel 23 may be of any desired material and shape. As shown in the drawing, it comprises a 10 glass tube 24, flanged at its outer surface at 25, and having a lower conical portion 26 provided with drip nozzle 27, controlled by valve 28. Glass tube 24 is provided with suitable unit indicia along its longitudinal surface by which to determine the volumetric flow of material passing from tube 24 to plate 2.

Tube 24 is fixedly held above plate 2 by flange 25 in registry with loop 29 rigidly secured to arm 30. Arm 30 is adjustably mounted on standard 31 through the medium of collar 32 and set screw 33. Standard 31 is rigidly secured to the framework of press 1 in a vertical position, in a manner not shown.

Description of the present invention with particular reference to the addition of an aldehyde solution to the ink supply during the printing operation is by way of illustration and not by way of limitation, it being understood that the present invention is adapted for the addition of any miscible fluid to the ink mixture during the printing operation. It will be understood that the term "ink" as used in this specification and in the claims is used in a broad sense and includes all marking substances which may be applied to 35 a printable surface by a printing press.

I claim:

1. In combination with a printing press having an inking plate and transfer means for transferring ink from the inking plate to the type of 40 said press, means including a drip vessel spaced from and above the inking plate for feeding miscible fluids to the inking plate for incorporation with ink during the printing operation.

2. In combination with a printing press having 45 an inking plate and transfer means for transferring ink from the inking plate to the type of said press, means including a drip vessel spaced from and above the inking plate for continuously feeding a volatile fluid to the inking plate for 50 incorporation thereon with ink during the printing operation.

3. In combination with a printing press including an inking plate adapted for periodic rotation and ink transfer rollers movable into contact with 55 the inking plate between periodic rotations of the inking plate to receive a supply of ink therefrom, means including a drip vessel spaced from and above the inking plate for feeding miscible fluids to the inking plate for incorporation with the ink 60 during the printing operation.

4. In combination with a printing press including an inking plate adapted for periodic rotation and ink transfer rollers movable into contact with the inking plate between periodic rotations of the 65 inking plate to receive a supply of ink therefrom, means including a drip vessel spaced from and above the inking plate for continuously feeding a volatile fluid to the inking plate for incorporation with the ink during the printing operation.

70 5. In combination with a printing press including an inking plate adapted for periodic rotation and ink transfer rollers movable into contact with the inking plate between periodic rotations of the inking plate to receive a supply of ink therefrom, 75 means for continuously feeding a volatile fluid to

the inking plate for incorporation with the ink during the printing operation, said means comprising a drip vessel spaced from and above the inking plate and having an opening relative to the inking plate, and means for controlling the flow of fluid passing from the opening to the inking plate.

6. In combination with a printing press including an inking plate adapted for periodic rotation and ink transfer rollers movable into contact with 10 the inking plate between periodic rotations of the inking plate to receive a supply of ink therefrom, means for continuously feeding a volatile fluid to the inking plate for incorporation with the ink during the printing operation, said means comprising a drip vessel fixedly mounted above the inking plate and having an outlet for the gravity flow of fluid from the vessel to the inking plate, and valve means for controlling the flow of fluid 15 through the outlet.

7. In combination with a printing press including an inking plate adapted for periodic rotation and ink transfer rollers movable into contact with the inking plate between periodic rotations of the inking plate to receive a supply of ink therefrom, 20 means for continuously feeding a volatile fluid to the inking plate for incorporation with the ink during the printing operation, said means comprising a drip vessel carried above the inking plate and having a lower conical portion provided with an opening for the gravity flow of 25 fluid from the vessel to the inking plate, a nozzle secured at the opening, and valve means in the nozzle for controlling the flow of fluid passing 30 from the vessel.

8. In combination with a printing press including an inking plate adapted for periodic rotation and ink transfer rollers movable into contact with the inking plate between periodic rotations of the inking plate to receive a supply of ink therefrom, 40 means for continuously feeding a volatile fluid to the inking plate for incorporation with the ink during the printing operation, said means comprising a drip vessel carried above the inking plate and having a lower conical portion provided with an opening for the gravity flow of 45 fluid from the vessel to the inking plate, a nozzle secured at said opening, and valve means in the nozzle for controlling the flow of fluid passing from the vessel, the vessel being provided with 50 unit indicia for determining the unit flow of fluid therefrom.

9. In combination with a printing press including an inking plate adapted for periodic rotation and ink transfer rollers movable into contact with the inking plate between periodic rotations of the inking plate to receive a supply of ink therefrom, 55 means for continuously feeding a volatile fluid to the inking plate for incorporation with the ink during the printing operation, said means comprising a drip vessel spaced from and above the inking plate and having a lower conical portion provided with an opening for the gravity flow of fluid from the vessel to the inking plate, a nozzle secured at the opening, valve means in the nozzle 60 for controlling the flow of fluid passing from the vessel, and means for adjustably supporting the vessel relative to the surface area of the inking plate.

10. In combination with a printing press including an inking plate adapted for periodic rotation and ink transfer rollers movable into contact with the inking plate between periodic rotations of the inking plate to receive a supply of ink therefrom, 70 means including a drip vessel spaced 75

from and above the inking plate for continuously feeding a volatile fluid to the inking plate for incorporation with the ink during the printing operation, the inking plate and the transfer rollers 5 providing means for intimately admixing the added fluid with the ink.

11. In combination with a printing press including an inking plate adapted for periodic rotation and ink transfer rollers movable into contact 10 with the inking plate between periodic rotations of the inking plate to receive a supply of ink therefrom, means for continuously feeding a vol-

atile fluid to the inking plate for incorporation with the ink during the printing operation, said means comprising a drip vessel spaced from and above the inking plate and having a lower conical portion provided with an opening for the gravity 5 flow of fluid from the vessel to the inking plate, a nozzle secured at the opening, and valve means in the nozzle for controlling the flow of fluid passing from the vessel, the inking plate and the rollers providing means for intimately admixing 10 the added fluid with the ink.

CHARLES T. WALTER.
